INVENTOR:
RUDOLF VON FROMMER
BY: Francis E. Bayne
ATTORNEY.

UNITED STATES PATENT OFFICE.

RUDOLF VON FROMMER, OF BUDAPEST, HUNGARY.

FIREARM.

Application filed April 24, 1924. Serial No. 708,764.

To all whom it may concern:

Be it known that I, RUDOLF VON FROMMER, a subject of Hungary, residing at Budapest, Hungary, have invented certain new and useful Improvements in or Relating to Firearms, of which the following is a specification.

This invention relates to operating-handles of the breech-bolt of firearms. The 10 handles of this kind heretofore known were rigidly secured to the breech, while the handle according to my present invention is capable of performing a relative movement with regard to the breech. The reason for 15 this arrangement is to effect proper engagement or disengagement between the breech or single parts thereof and other elements of the gun in a simple way, such engagement or disengagement being simultaneous 20 with the forward or rearward movements of the breech-bolt.

For attaining this end an angle-lever has heretofore been provided near or on said handle pressed on the same when operated, 25 and when the breech-bolt was performing its forward or rearward movement a coupling has been locked or unlocked by said lever. These known arrangements were very complicated, and as a further disadvantage special care must have been taken 30 when operating them. Through my present invention however, I am able to provide a most simple construction by the aid of which the above mentioned end can be attained 35 much easier and this by the arrangement that the said operating-handle itself, which must by all means be grasped when working the breech effects the disengagement of the coupling element or allows the same to 40 be automatically engaged, whereby no special care must be taken, as no separate part is to be worked together with the handle. In the accompanying drawing two forms of 45 the improved arrangement are shown by way of example.

Fig. 1 is a longitudinal sectional view of one part of the breech-bolt the operating-handle being pivotally attached to the same.

Fig. 2 shows a modification in a sectional 50 view; the operating handle in this case being pivotally secured to an opening-bar attached to the breech.

According to the arrangement shown in Fig. 1 the operating-handle 1 is pivotally 55 attached to the breech-bolt 3 by means of a pivot 2. The operating-handle 1 is capable

of being slightly swung by the provision of a split 4 left between the projection 13 of the coupling lever 7 and the striking-face 6 of the breech-bolt. The operating-handle 60 1 rests in front, at 5, against the breech-bolt, and behind at 20 against the projection 13 so that when the operating-handle is being swung its forward movement is limited at 5 whilst its rearward movement is limited at 6. Pivoted on pin 2 there is a coupling-lever 7 interlocking the breech-bolt with one of the rigid parts, say with part 8 of the firearm. The coupling-lever 7 has a tappet 9 subject to the pressure of 65 the firing-spring 12. The action of spring 12 is transmitted to tappet 9 by means of a pressure ring 10 put on the firing-pin 11 and forming the back support of the spring 12. The operating-handle 1 is pressed forward 70 by the pressure-ring 10 subject to the action of the firing-spring 12 so that the operating-handle 1 rests in its normal position against the breech-bolt 3 at 5. If the breech to be opened by pulling the operating-handle 80 1 backward, the stress acting upon the operating-handle will swing the same on pin 2, and first of all by means of the projection 13 the coupling-lever 7 is lifted from its normal position, and thus disengagement is effected between the hook of the coupling-lever 7 and the part 8 of the gun, whereupon the breech may readily be opened. When the breech is moved forward—whereby the operating-handle 1 is swung back in its normal position—re-engagement between the coupling-lever 7 and the rigid part 8 of the gun may take place under the action of the firing-spring 12 without the operating-handle 1 having been influenced, for the 85 coupling-lever 7 when passing over the inclined surface 15 of part 8 with its curved surface 14 is enabled by split 4 to swing upwards without the operating-handle being forced to swing backwards on pin 2. 90

In the form shown in Fig. 2 the operating handle 1 is also enabled to be swung, and is pivotally attached to the closing-rod 3. The tappet 9 and projection 13 of the coupling-lever 7 act in the same manner as described in connection with Fig. 1. The tappet 9 is subject to the pressure of spring 16 whereby the action of the latter is transmitted to the tappet 9 by pin 17. The coupling lever 7 is able to be interlocked with the movable rod 18 by means of the curved surface 14 in the same manner as in the 95 100 105 110

construction described in connection with Fig. 1 with the rigid part 8 of the gun.

Claims:

1. In a firearm, the combination of a breech-bolt, an operating handle therefor swingably connected to said breech-bolt, a coupling member movably connected to said operating handle for coupling the same with a part of the firearm, means on said handle for operating said coupling member in one direction, and a spring for operating the coupling member in the opposite direction independently of the swinging movements of the handle relatively to the breech-bolt.
2. In a firearm, the combination of a breech-bolt, an operating handle therefor swingably connected to said breech-bolt, a coupling member movably connected to said operating handle for coupling the same with a part of the firearm, a pivot pin pivotally connecting the handle and the coupling member with the breech-bolt, said coupling

member having a projection adapted to be engaged by the handle for operating the coupling member in one direction, and a spring for actuating the coupling member in the opposite direction.

3. In a firearm, the combination of a breech-bolt, an operating handle therefor swingably connected to said breech-bolt, a coupling member movably connected to said operating handle for coupling the same with a part of the firearm, means on said handle for operating said coupling member in one direction, a firing spring, means for transmitting the action of said firing spring to the coupling member in the opposite direction independently of the swinging movements of the handle relatively to the breech-bolt.

In testimony whereof I affix my signature.

RUDOLF von FROMMER.
